METHOD AND APPARATUS FOR STRIPPING
WELL PIPES

Glenn D. Johnson, Downey, and William F. Bates, Ar-
cadia, Calif., assignors to Shell Oil Company, New
York, N.Y., a corporation of Delaware

Filed June 22, 1961, Ser. No. 118,989
18 Claims. (Cl. 166—46)

This invention relates to a method and apparatus for running pipe in and out of a well and pertains more particularly to a method of inserting into or removing from a well a string of pipe which surrounds a second string a pipe of a smaller diameter or a well tool which must be held in tension in the well to prevent it from dropping to the bottom of the well.

The operation of inserting a pipe into a well or removing it therefrom, when the pipe surrounds a second pipe or an elongated object already disposed within the well, is commonly referred to as "stripping."

In an attempt to locate new oil fields an increasing amount of well drilling has been conducted at off-shore locations, such, for example, as off the coast of Louisiana, Texas and California. As a general rule, the strings of casing in a well, together with the tubing string or strings, extend to a point well above the surface of the water where they are closed in the conventional manner that is used on land wells, with a conventional wellhead assembly being attached to the top of the casing. Attempts have been made recently to provide methods and apparatus for drilling, completing and working-over a well wherein both the well casinghead and the various well components secured thereto or suspended therefrom are located underwater at a depth sufficient to allow ships to pass over them. Preferably, the casinghead and its associated equipment are located close to the ocean floor. In order to install equipment of this type under water in depths greater than the shallow depth at which a diver can easily operate, it has been necessary to design entirely new equipment for this purpose.

In one such method of drilling off-shore wells wherein a wellhead base structure is positioned on the ocean floor, strings of pipe, made up of many sections of pipe fastened together, are stripped in and out of the well by the method and apparatus of the present invention.

It is the primary object of the present invention to provide a method and apparatus, the apparatus being simple in design and easy to operate, whereby a larger internal-diameter pipe may be stripped into a well over a smaller diameter pipe or a well tool of smaller diameter.

A further object of the present invention is to provide apparatus for stripping pipe into an off-shore well from a platform positioned above the ocean surface, while maintaining a constant tension on an inner pipe string of smaller diameter over which the larger diameter pipe string is being stripped.

Another object of the present invention is to provide simple and safe apparatus adapted to be connected to and locked on an inner string of pipe to be held in constant tension while an outer string of pipe is stripped over it.

These and other objects of this invention will be understood from the following description taken with reference to the drawing, wherein:

FIGURE 1 is a longitudinal diagrammatic view illustrating cutaway sections of a derrick together with the hoist systems mounted in the derrick in accordance with the present invention;

FIGURE 2 is a longitudinal view taken in partial cross section of one form of a connector base to which a connector element has been secured and locked;

FIGURE 3 is a plan view of the apparatus shown in FIGURE 2;

2

FIGURES 4 and 5 are isometric views of the connector element and connector base, respectively, illustrated in FIGURE 2;

FIGURE 6 is a fragmentary isometric view illustrating the locking sleeve normally carried in the connector base of FIGURE 2;

FIGURES 7 through 11 are schematic views illustrating the stepwise operations of carrying out the method of the present invention;

FIGURES 12 and 14 are longitudinal views of alternate forms of a connector base in accordance with the present invention;

FIGURES 13 and 15 are longitudinal views of alternate forms of connector devices adapted to engage in cooperating engagement with the connector bases of FIGURES 12 and 14, respectively; and

FIGURE 16 is a plan view taken along the line 16—16 of FIGURE 14.

Referring to FIGURE 1 of the drawing, numerals 11 and 12 represent fragments of a well derrick, such for example as the type used in drilling wells, which would extend down to an operational base or floor 13, which may be the floor of a derrick or a floor of a drilling platform, either stationary or floatable, as used in drilling off-shore wells. The derrick 11-12 is provided with a conventional hoist system including a crown-block 14, a traveling block 15 and fall lines 16. Secured to the lower end of the traveling block 15 are elevator links 17 which suspend a conventional elevator 18. The elevator 18 is designed to clamp around the upper end of a larger internal-diameter pipe string 20, or a section thereof, for raising or lowering the pipe string.

The derrick 11-12 is also provided with another pair of hoist systems comprising hoists 21 and 22, hoist lines 23 and 24, sheaves 25 and 26, and connector elements 27 and 28 carried at the end of the hoist lines 23 and 24. In the event that the present hoist systems were mounted on a floating drilling barge adapted to move up and down with relation to a wellhead positioned on the ocean floor, the hoists 21 and 22 would be preferably constant tension hoists.

Positioned substantially axially within the larger diameter outer pipe string 20a is a smaller-diameter inner pipe string 30 having a connector base 31 secured to the top thereof which is adapted to be locked to either of the connector elements 27 or 28. The pipe string 20a is illustrated as extending through a hole 32 in the floor of the derrick, and through a spider or rotary table 33 in which slips 34 are wedged in order to hang the pipe string 20a therefrom.

In FIGURE 2, one form of a connector base 31 comprises a body member 35 having an upwardly-extending mandrel section 36 of smaller diameter, with a pair of locking or latching lugs 37 and 38 formed on or fixedly secured thereto. The lugs 37 and 38 are positioned diametrically opposite each other on the mandrel 36 and extend outwardly therefrom.

The connector element 27 is illustrated as being provided with an opening 40 in the body thereof for receiving and locking therein one lug, in this case lug 37 of the connector base 31. The hoist cable 23 is fixedly secured to the top of the connector element 27 in any suitable manner, as by a split thimble 41 and a lead upset 42. The opening 40 is more clearly shown in the isometric view of FIGURE 4. The upper end of the opening 40 is wider, as at 40a, than the lower portion at 40b, the bottom of the connector element 27 being closed, as at 43, so as to support a locking lug 37 or 38 of the mandrel 36. As shown in FIGURE 5 some of the wider portion 37a of the lug 37 is adapted to pass through the wide opening 40a in the connector element 27 while the grooved

portion 37b of the locking lug 37 is adapted to seat within the narrow opening 40b of the connector device 27.

To prevent the connector element 27 (FIGURE 2) from becoming accidentally unlatched from the locking lug 37 of the connector base 31, the connector base 31 is provided with suitable locking means which may take the form of a sleeve 44 mounted in the top of the body member 35 for rotational movement about the mandrel 36. The locking sleeve 44 is retained in the body member 35 by means of a ring 45 or other suitable means. A spring 46 mounted within the body member 35 is adapted to bear against a flange 47 carried at the lower end of the sleeve 44 for pressing the flange 47 downwardly against a positioning ball or orienting element 48. These elements are more clearly shown in the disassembled view of a portion of the connector base as shown in FIGURE 6. Here it is shown that the bottom face of the flange 47 is provided with a pair of diametrically-positioned grooves 50 and 51 which are aligned with the center line of a slot 52 cut in the side of the locking sleeve 44 which extends downwardly from the top thereof, as illustrated. The sleeve 44 may be provided with one or more holes 53 extending through the wall thereof into which a pin can be positioned for turning the sleeve. The slot 52 in the locking sleeve 44 should be slightly wider than the widest part of either locking lug 37 or 38 carried at the upper end of the connector base 31. The height of the sleeve would be such that, as shown in FIGURE 2, the sleeve 44 may be rotated under the lower end 43 of the connector element 27 when it is engaged and with the bottom of the locking lug 37 of the mandrel 36 thus locking the connector element to the connector base 31. To unlock the connector device so that the connector element 27 can be detached from the locking lug 37, the locking sleeve 44 would be rotated 180°, or until the groove 50 (FIGURE 6) seated on the ball 48, at which time the slot 52 in the locking sleeve 44 would be positioned beneath the closed end 43 of the connector element 27, allowing it to be moved downwardly into the slot 52 at which time the enlarged portion 37a of the locking lug would be opposite the wide portion 40a of the opening 40 so that the connector element 27 could be removed laterally from the locking lug 37.

The lower end of the connector base 31 is provided with suitable means, such as screw threads 54, whereby the connector base 31 may be removably secured to the top of the smaller-diameter inner pipe string 30 (FIGURE 1). It is to be understood that any other suitable form of a device for latching onto the inside or the outside of a pipe may be employed for securing the connector base 31 (FIGURE 2) to a smaller diameter tubular pipe string 30 or other elements over which pipe is to be stripped. Thus, for example, in FIGURE 12 a connector base 55 is illustrated as being provided diagrammatically with an internal pipe spear comprising a pair of pivotally-mounted spear arms 60 and 61 having teeth 62 and 63 thereon, respectively, and being suspended from the lower end of the connector base 55. The mandrel 55 is actually slidable relative to the base 55 and has fixedly secured to the lower end of the mandrel a wedge element 64 adapted to contact tapered faces 65 and 66 on the spear arm 60 and 61. Thus, on applying tension to the mandrel 56 the wedge element 64 forces the teeth 62 and 63 against the inner surface of a pipe string surrounding it.

In the form of the connector base 55 shown in FIGURE 12, the dual mandrel section 56-57 is provided with slots 67 and 68 therein for receiving a locking lug 70 of a connector element 71 which would be secured to a cable 72. The form of the slots 67 and 68 of the apparatus in FIGURE 12 would be identical with the slots shown in FIGURE 4 if turned upside down. Another form of a connector base together with cooperating connector elements is shown in FIGURES 14, 15 and 16 as comprising a connector base 74 having a mandrel

75 extending upwardly therefrom in which a pair of locking recesses 76 and 77 are formed for receiving hooks 78 of a suitable design for cooperating therein. The hooks 78 would be carried by the connector elements 80 and 81.

In performing an operation in accordance with the present invention of stripping a larger internal diameter pipe into a well over a smaller diameter pipe, the operation would start as illustrated in FIGURE 7 with the larger diameter pipe 20a being held by means of slips 34 in a fixed position within the spider or rotary table 33. At the same time the connector base 31 (FIGURE 2) would be secured to the top of the smaller diameter pipe string 30 (FIGURE 7) with the connector element 28 secured to the lower end of hoist line 24, being connected to one lug of the connector base 31 so that the tension on the cable 24 could hold the connector base 31 above the upper end of the pipe string 20a. With connector element 28 and its hoist cable 24 being employed in this manner, the other connector element and its cable 23 (FIGURE 7) would be run down another section of pipe 20 which is to be added to pipe 20a already suspended from slip 34. The elevator 18 would be connected to one end of the pipe section 20 to be added and it would be hoisted to a position shown in FIGURE 8 by means of the main hoist system of the derrick. With the new section 20 of pipe suspended in this position, the connector element 27 extending therethrough would be carried over manually to the locking lug 37 and locked thereon as shown in FIGURE 9. At this time the pipe section 20 and the cable 23 carried therein would be moved into substantially longitudinal relationship with the pipe string 20a already in the well, as shown in FIGURE 10. Tension would then be applied to cable 23 and its connector element by means of the hoist 21 (FIGURE 1), at which time the weight of the inner pipe string 30 would be transferred from connector element 23 to connector element 27. With the cable 23 and its connector element 27 now supporting the inner pipe string 30, the other connector element 28 and its cable 24 are disconnected from the locking lug 38 of the connector base 31 and removed therefrom.

The additional section of pipe 20 is then lowered down over the cable, connector element 27, connector base 21 and inner pipe string 30 until the threads 82 at the lower end of the pipe section 20 engage the threads in the upper section of the pipe 20a and may be rotated therein, for coupling the two pipe sections together. While this operation is going the other connector element 28 and its cable 24 may be run down through another section pipe 50 to be added to the larger internal diameter pipe string, as shown in FIGURE 7. After the new section 20 (FIGURE 11) was secured to the pipe string 20a, the slips 34 would be removed while the elevator 18 (FIGURE 1) supported the larger internal diameter pipe string and lowered it into the well until the connector base 31 was above the upper end of the larger internal diameter pipe string, as shown in FIGURE 7, at which time the slips 34 would again be inserted around the pipe string 20a to suspend it in place. By repeating the cycle of operation described, the desired amount of pipe may be stripped into a well. It may be seen that since the pipe section 20 must be positioned vertically above the pipe section 20a, the sheaves 25 and 26 (FIGURE 1) must be positioned on the derrick at a height sufficient to accommodate a pipe section in the manner described.

To remove a larger diameter pipe from a well and strip it out of a smaller diameter pipe, the above-described procedure would be reversed. After connector element 27 was secured to the connector base, the upper pipe section 20 would be raised by means of elevator 18 (FIGURE 1) and unscrewed and elevated from that section 20a, to expose the connector base 31 as shown in FIGURE 11. The connector device 28 would then be brought into position and latched on the connector base 31 and tension applied to its cable 24 to pick up the weight of

the inner pipe string 30, as shown in FIGURE 10. Connector 27 would then be detached from the connector base 31, as shown in FIGURE 8, and the connector device 27 and its cable 23 would be pulled out of the pipe section 20, as shown in FIGURE 7, while the other cable 24 and its connector device 28 supported the inner pipe string 30.

We claim as our invention:

1. A method of stripping a larger internal diameter outer pipe string over a smaller diameter inner elongated member, said method comprising the sequential steps of connecting a first suspending cable to said inner member, applying tension to said first cable to suspend said inner member therefrom, running a second cable through a section of larger internal diameter outer pipe to be added to the top of said previously positioned outer pipe string, connecting said second cable to said inner member, moving said pipe section to be added and said second cable carried therein into substantial longitudinal position above said suspended outer pipe string, applying tension to said second cable to suspend said inner member therefrom, disconnecting said first cable from said inner member, lowering said larger internal diameter pipe section into engagement with said outer pipe string and connecting the two pipes together.

2. A method of stripping a larger internal diameter outer pipe string over a smaller diameter inner elongated member, said method comprising the sequential steps of fixedly suspending said pipe string, connecting a first suspending cable to said inner member, applying tension to said first cable to suspend said inner member therefrom, running a second cable through a section of larger internal diameter outer pipe to be added to the top of said outer pipe string, connecting the lower end of said second cable to said inner member, moving said pipe section to be added and said second cable carried therein into substantial longitudinal position above said suspended outer pipe string applying tension to said second cable to suspend said inner member therefrom, disconnecting said first cable from said inner member, lowering said larger internal diameter pipe section into engagement with said outer pipe string, connecting the pipe section to said pipe string, and lowering said outer pipe string until the top of the inner member emerges therefrom.

3. A method of stripping a larger internal diameter outer pipe string over a smaller diameter inner pipe string, said method comprising the sequential steps of fixedly suspending said outer pipe string, attaching a dual connector base to the top of the inner pipe string, connecting a first suspending cable to said connector base, applying tension to said first cable to suspend said inner pipe string therefrom, running a second cable through a section of larger internal diameter outer pipe to be added to the top of said outer pipe string, connecting the lower end of said second cable to said connector base, moving said outer pipe section to be added and said second cable carried therein into substantial longitudinal position above said suspended outer pipe string, applying tension to said second cable to suspend said inner pipe string therefrom, disconnecting said first cable from said connector base, lowering said larger internal diameter pipe section into engagement with said outer pipe string and connecting the pipe section to said outer pipe string.

4. A method of stripping a larger internal diameter outer pipe string over a smaller diameter inner pipe string, said method comprising the sequential steps of fixedly suspending said outer pipe string, attaching a dual connector base to the top of the inner pipe string, connecting a first suspending cable to one side of said connector base, applying tension to said first cable to suspend said inner pipe therefrom, running a second cable through a section of larger internal diameter outer pipe to be added to the top of said outer pipe string, connecting the lower end of said second cable to the other side of said connector base, moving said outer pipe section to be added and said second cable carried therein into substantial longitudinal position

5 above said suspended outer pipe string, applying tension to said second cable to suspend said inner pipe string therefrom, disconnecting said first cable from said connector base, lowering said larger internal diameter pipe section into engagement with said outer pipe string and connecting the pipe section to said outer pipe string, lowering said outer pipe string until the connector base at the top of the inner pipe string emerges therefrom, and anchoring said outer pipe string against axial movement.

5. Apparatus for use in oil well operations for selectively stripping to and from a well a larger internal diameter vertical outer pipe string over a smaller diameter elongated inner member held in tension throughout the operation, said apparatus comprising first and second and third hoist means having respectively first and second and third hoist cable means with first and second and third connector means carried thereby, said first connector means being pipe connector means of a size to connect onto the upper end of the larger internal diameter outer pipe string, an operational base including support means for mounting all of said hoist means thereabove, and slip-type anchoring means for engaging the larger internal diameter outer pipe string and temporarily securing it relative to said base against downward axial movement, said second and third connector means being connectible to said inner member and of a size to pass through said outer pipe string.

6. Apparatus for use in oil well operations for selectively stripping to and from a well a larger internal diameter vertical outer pipe string over a smaller diameter vertical inner pipe string held in tension throughout the operation, said apparatus comprising first and second and third hoist means having respectively first and second and third hoist cable means with first and second and third pipe connector means carried thereby, said first connector means being elevator means of a size to connect onto the upper end of the larger internal diameter outer pipe string, an operational base including support means for mounting all of said hoist means thereabove, and slip-type anchoring means for engaging the upper end of the larger internal diameter outer pipe string and temporarily securing it to said base against downward axial movement, said second and third pipe connector means being connectible to said inner pipe string and of a size to pass through said outer pipe string.

7. Apparatus for use in oil well operations for selectively stripping to and from a well a larger internal-diameter vertical outer pipe string one section at a time over a smaller-diameter vertical inner pipe string held in constant tension throughout the operation, said apparatus comprising first and second and third hoist means having respectively first and second and third hoist cable means with first and second and third pipe connector means carried thereby, said first connector means being elevator means of a size to connect onto the upper end of the larger internal diameter outer pipe string, an operational base including support means for mounting all of said hoist means thereabove, slip-type anchoring means for engaging the upper end of the larger internal diameter outer pipe string and temporarily securing it to said base against downward axial movement, and a connector base including means for securing it temporarily to the upper end of the smaller-diameter inner pipe string, said connector base including cooperating engaging means adapted to connect releasably to said second and third connector means carried by said second and third hoist means, said second and third connector means and said connector base being of a size to pass through said outer pipe string.

8. Apparatus for use in oil well operations for selectively stripping into and out of a well a larger internal diameter vertical outer pipe string one section at a time over a smaller-diameter vertical inner pipe string held in constant tension throughout the operation, said apparatus comprising first and second and third hoist means

7
having respectively first and second and third hoist cable means with first and second and third pipe connector means carried thereby, said first connector means being elevator means of a size to connect onto the upper end of the larger international diameter outer pipe string, an operational base including support means for mounting all of said hoist means thereabove, slip-type anchoring means for engaging the upper end of the larger internal diameter outer pipe string and temporarily securing it to said base against downward axial movement, a connector base including means for securing it temporarily to the upper end of the smaller-diameter inner pipe string, said connector base including cooperating engaging means adapted to receive said second and third connector means carried by said connector base for selectively locking one of said second and third connector means thereto, said second and third connector means and said connector base being of a size to pass through said outer pipe string, said second and hoist cable means being slightly greater in length than the length of a section of said outer larger internal diameter pipe.

9. A method of stripping a larger internal diameter outer pipe string over a smaller diameter inner elongated member, said method comprising the sequential steps of fixedly suspending said outer pipe string, connecting a first suspending cable to said outer pipe string, applying tension to said first cable to suspend said inner member therefrom, raising the outer pipe string with said first cable inside it until at least one section thereof is above its previously-suspended position, again fixedly suspending said outer pipe string, disconnecting at least one pipe section from the top of said outer pipe string, raising said disconnected pipe section until at least the top of the inner member is exposed therebelow, connecting a second cable to the inner member, moving said second cable into a substantially longitudinal position outside said disconnected pipe section, applying tension to said second cable to suspend said inner member therefrom, and disconnecting said first cable from said inner member.

10. A method of stripping a larger internal diameter outer pipe string over a smaller diameter inner elongated member, said method comprising the sequential steps of fixedly suspending said outer pipe string, attaching a dual connector base to the top of the inner member, connecting a first suspending cable to said connector base, applying tension to said first cable to suspend said inner member therefrom, raising the outer pipe string with said first cable inside it until at least one section thereof is above its previously suspended position, again fixedly suspending said outer pipe string, disconnecting at least one pipe section from the top of said outer pipe string, raising said disconnected pipe section until the connector base at the top of the inner member is exposed therebelow, connecting a second cable to said connector base, moving said second cable into a substantially longitudinal position outside said disconnected pipe section, applying tension to said second cable to suspend said inner member therefrom, disconnecting said first cable from said connector base, moving said larger internal diameter pipe section to one side of said suspended pipe string, and withdrawing said first cable from said pipe section.

11. A method of stripping a larger internal diameter outer pipe string over a smaller-diameter inner pipe string, said method comprising the sequential steps of fixedly suspending said outer pipe string, connecting a first suspending cable to said inner pipe string, applying tension to said first cable to suspend said inner pipe string therefrom, raising the outer pipe string with said first cable inside it until at least one section thereof is above its previously suspended position, again fixedly suspending said outer pipe string, disconnecting at least one pipe section from the top of said outer pipe string, raising said disconnected pipe section until at least the top of the inner pipe string is exposed therebelow, con-

necting a second cable to said inner pipe string, moving said second cable into a substantially longitudinal position outside said disconnected pipe section, applying tension to said second cable to suspend said inner pipe string therefrom, and disconnecting said first cable from said inner pipe string.

12. A method of stripping a larger internal diameter outer pipe string over a smaller diameter inner pipe string being held in tension, said method comprising the sequential steps of fixedly suspending both pipe strings, attaching a dual connector base to the top of the inner pipe string, connecting a first suspending cable to one side of said connector base, applying constant tension to said first cable to suspend said inner pipe string therefrom, raising the outer pipe string with said first cable inside it until at least one section thereof is above its previously suspended position, again fixedly suspending said outer pipe string, disconnecting at least one pipe section from the top of said outer pipe string, raising said disconnected pipe section until the connector base at the top of the inner pipe string is exposed therebelow, connecting the lower end of a second cable to the other side of said connector base, moving said second cable into a substantially longitudinal position outside said disconnected pipe section, applying tension to said second cable to suspend said inner pipe string therefrom, disconnecting said first cable from said connector base, moving said larger internal diameter pipe section to one side of said suspended pipe strings, and withdrawing said first cable from said pipe section.

13. A method of stripping a larger internal-diameter outer pipe string over a smaller-diameter inner elongated member, said method comprising the sequential steps of
(a) connecting a first suspending element to said inner member to suspend said inner member relative to said large internal-diameter outer pipe string,
(b) running a second suspending element through a section of larger internal-diameter outer pipe to be added to the top of said outer pipe string,
(c) suspending and moving said pipe section to be added and said second suspending element carried therein into substantial longitudinal position above said suspended outer pipe string,
(d) connecting said second suspending element to said inner member,
(e) transferring the weight of said inner member from said first suspending element to said second suspending element,
(f) disconnecting said first suspending element from engagement with said inner member,
(g) lowering said larger internal-diameter pipe section into engagement with said outer pipe string while maintaining said inner member in tension within said outer pipe string, and
(h) connecting the pipe section to the pipe string.

14. The method of claim 1 wherein the weight of said inner member is transferred to said second suspending element by applying tension to said second suspending element.

15. A connector system having one member carried at one end of a substantially vertical elongated member for selectively securing one of a pair of cooperating members thereto, said connector system comprising a latch-carrying body member having latch means carried thereby and a cooperating latch-receiving body member, one each of one of said body members carried at the end of each of a pair of cable means, and means removably securing said other body member to one end of an elongated member, one of said body members being adapted to latchingly receive two of said other body members.

16. A connector system having one member carried at the upper end of a substantially vertical elongated member for selectively securing one of a pair of cooperating members thereto, said connector system comprising a

latch-carrying body member having latch means carried thereby and a cooperating latch-receiving body member, one each of one of said body members carried at the end of each of a pair of hoist cable means, hoist means having said hoist cable means secured thereto for applying tension thereto, means fixedly securing one of said other body members to the upper end of said elongated member, one of said body members being adapted to latchingly receive two of said other body members.

17. A connector system having one member carried at the upper end of a substantially vertical section of pipe for selectively securing one of a pair of cooperating members thereto, said connector system comprising a latch-carrying body member having latch means carried thereby and a cooperating latch receiving body member, one each of one of said body members carried at the end of each of a pair of hoist cable means, hoist means having said hoist cable means secured thereto for applying tension thereto, means fixedly securing one of said body members to the end of each of said hoist cable means, and means removably securing said other body member to one end of a string of pipe, one of said body members being adapted to latchingly receive two of said other body members.

18. A connector system having one portion carried at the upper end of a substantially vertical section of pipe for selectively securing one of a pair of cooperating latching elements thereto, said connector system comprising latch-carrying body members having latch means carried thereby and a cooperating latch-receiving body member, one of said latch-carrying body members carried at the end of each of a pair of hoist cable means, hoist means having said hoist cable means secured thereto for maintaining constant tension thereon, and means removably securing said latch receiving body member to one end of a string of pipe, said latch-receiving body being adapted to receive two of said latch-carrying body members.
